UNITED STATES PATENT OFFICE

ARTHUR B. MODINE, OF RACINE, WISCONSIN

RADIATOR CONSTRUCTION

Application filed September 25, 1925. Serial No. 58,538.

My invention relates to radiators and particularly to radiators adapted for use in the cooling systems of internal combustion engines and the like. The invention has among 5 its other objects the production of devices of the kind described which are compact, durable, efficient and satisfactory for use wherever found applicable. A particular object of the invention is to produce devices 10 of the kind described wherein there will be exceedingly efficient heat exchange between the water flowing through the tubes and the air passing around the tubes. Another particular object of the invention is to utilize 15 substantially all of the metal from which the parts of the radiator are formed, the metal displaced to provide apertures being formed into fins or flanges.

Many other objects and advantages of the 20 construction herein shown and described will be obvious to those skilled in the art from the disclosure herein given.

To this end my invention consists in the 25 novel construction, arrangement and combination of parts herein shown and described, and more particularly pointed out in the claims.

In the drawings, wherein like reference 30 characters indicate like or corresponding parts:

Fig. 1 is a fragmentary front elevation of a radiator embodying my invention;

Fig. 2 is a fragmentary section taken on 35 line 2—2 of Fig. 1;

Fig. 3 is a fragmentary section taken on the line 3—3 of Fig. 2;

Fig. 4 is a fragmentary section taken on the line 4—4 of Fig. 2;

Fig. 5 is a fragmentary elevation of one 40 of a plurality of plates which form parts of the radiator shown in Fig. 1, the plate being shown in an intermediate stage of manufacture;

Fig. 6 is a fragmentary elevation of the 45 plate shown in Fig. 5, the plate being shown in another stage of manufacture;

Fig. 7 illustrates the manner in which the 50 plate shown in Figs. 5 and 6 is assembled with the water tubes of the radiator;

Fig. 8 is a fragmentary section illustrating another form of the invention;

Fig. 9 is a section taken on line 9—9 of Fig. 8;

Fig. 10 is a fragmentary elevation of one 55 of a plurality of plates which form parts of the radiator shown in Fig. 8, the plate being shown in an intermediate stage of manufacture;

Fig. 11 is a fragmentary section taken 60 through a radiator embodying another form of the invention, and

Fig. 12 is a section taken on line 12—12 of Fig. 11.

Referring for the present to Figs. 1 to 7, 65 inclusive, wherein I have illustrated my improved construction embodied in a radiator adapted for use in automobiles, aeroplanes and the like, the reference characters 10 and 11 designate water tubes and plates, respectively, the water tubes 10 being mounted in apertures 13 formed in the plates 11 and being held in spaced relation by the plates. The tubes 10 are preferably formed from relatively thin sheet metal, the front and rear edges of the tubes being rounded as at 14 and the side walls thereof being flattened as at 14^a. It will be noted that the tubes are relatively narrow, and that they extend from adjacent the front edges of the plates to adjacent the rear edges thereof.

In Figs. 5 and 6 I have illustrated the 75 method which I practise to produce the plates 11. A plurality of longitudinal slits 15 and a plurality of transverse slits 16 are punched in each of the plates 11. The slits 15 are arranged in pairs, each pair being connected by one of the slits 16. A plurality of diagonal slits 18 are also punched in each plate 11, the slits 18 being arranged in such manner that tongues or vanes 19 may be struck up from the plates. The slits 15 and 16 are so arranged that inclined flanges 21 may be struck up from the plates in the operation in which the apertures 13 are formed 80 therein, as shown in Figs. 3 and 6. The metal which is displaced when the ends of the apertures 13 are formed, is formed into arcuate flanges 23 adapted to engage the front and rear edges of the tubes 10. In the embodiment 85

ment of the invention which is illustrated in Figs. 1 to 7, inclusive, the tongues or vanes 19 are arranged at those points at which the inclined flanges 21 join the plates 11. The inclined flanges 21 are so formed that their free edges will contact with the flattened sides 15 of the tubes 10. The plates 11 are coated with any suitable substance to which solder does not readily adhere. These coatings may 10 be applied to the plates before or after the flanges 21 and 23 have been formed thereon. If the flanges 21 and 23 are formed after the plates have been coated, it is obvious that the edges of the flanges 21 and the inner surfaces 15 of the flanges 23 will be substantially clean and free from the coating substance. If the coatings are applied after the flanges 21 and 23 have been formed, the edges of the flanges 21 and the inner surfaces of the flanges 23 are 20 cleaned in any suitable manner and by any suitable apparatus.

To permanently assemble the tubes 10 and plates 11, I preferably practise my improved method which is more fully described in my 25 copending application, Serial No. 58,542, filed Sept. 25, 1925. The tubes 10 and plates 11 are assembled to occupy the relative positions wherein they are shown in Fig. 1. The radiator is then held in a substantially horizontal 30 position and dipped a short distance into a bath of fused solder whereupon capillary attraction causes the solder to flow upon the tubes 10 at the points where they are contacted by the free edges of the flanges 21 and the 35 inner surfaces of the flanges 23. Of course, to solder the inner surfaces of the flanges 23 located on the upper side of the radiator, it is necessary to invert the radiator and again dip it a short distance in the bath of solder. 40 When the radiator is then withdrawn from the solder, the plates and tubes are rigidly secured to each other.

The above described construction insures 45 that there will be exceedingly efficient heat exchange between the walls of the tubes 10 and the plates 11, as the heat readily flows through the soldered connections. It also insures that there will be a maximum transfer 50 of heat between the water in the tubes 10 and the air passing through the radiator as the 55 plates serve as cooling fins for the tubes and the flanges 23 and the tongues or vanes 19 create a turbulence in the air passing through the radiator so that substantially all of the 60 air passing through the radiator comes in contact with the tubes. It will be noted that the tongues or vanes 19 project from the sides of the plates 11 and that substantially half of them point toward the rear of the radiator 65 while the remaining half point toward the front of the radiator. It will also be noted that the metal displaced to provide the apertures 13 is formed into the flanges 21 and that there is no waste of material. 70 As hereinbefore set forth, the tubes 10 are

made from relatively thin sheet metal and are relatively narrow. Obviously, this construction adds to the efficiency of the radiator as there will be a relatively high percentage of heat exchange between the water and the 70 walls of the tubes.

In Figs. 8, 9 and 10 I have illustrated radiator construction which, in general, is substantially identical with the radiator construction illustrated in Figs. 1 to 7, inclusive. However, in the radiator construction illustrated in Figs. 8 to 10, inclusive, the tongues or vanes 19 are omitted and a plurality of tongues or vanes 19^a and 19^b of 75 substantially identical form are employed in place thereof. The vanes 19^a and 19^b are arranged substantially centrally of the inclined flanges 21, the vanes 19^a projecting from the upper sides of the flanges 21, and the vanes 19^b projecting from the lower sides of the 80 flanges 21.

In Figs. 11 and 12, I have shown still another form of the invention embodied in a radiator which is substantially identical with the radiator shown in Figs. 1 to 7, inclusive, 90 with the exception that the tongues or vanes 19 are omitted therefrom. In the radiator construction shown in Figs. 11 and 12, a plurality of pointed lugs 19^c are formed upon the upper surfaces of the inclined flanges 21. The pointed lugs 19^c are formed by punching them of the metal from which the inclined flanges are formed, thus leaving a plurality of depressions 10^d upon the undersides of the flanges. The pointed lugs 19^c are adapted to 95 cause a turbulence in the air passing through the radiator so that substantially all of it will come in contact with the tubes 10 and plates 11.

Having thus described my invention, it is 100 obvious that various immaterial modifications may be made in the same without departing from the spirit of my invention; hence I do not wish to be understood as limiting myself to the exact form, construction, arrangement and combination of parts herein 105 shown and described, or uses mentioned.

What I claim as new and desire to secure by Letters Patent is:

1. In a device of the kind described, a plurality of substantially flat plates, flanges struck up from said plates to form apertures therein, tubes provided with substantially flat sides and arranged in said apertures, said apertures being larger than said tubes and 115 said flanges being arranged to engage said tubes, the flanges being of such size and shape 120 that air may pass freely between any one of said tubes and the flanges engaging it, and smaller flanges struck up out of said plate 125 and arranged to direct air through said flanges toward said tubes.

2. In a device of the kind described, a plurality of substantially flat plates, flanges struck up from said plates to form apertures 130

therein, tubes provided with substantially flat sides and arranged in said apertures, said apertures being larger than said tubes and said flanges being arranged to engage said tubes, the flanges being of such size and shape 5 that air may pass freely between any one of said tubes and the flanges engaging it, and projections formed upon said flanges to increase the exchange of heat between them and 10 the air, said flanges being perforated to permit passage of air therethrough.

3. In a device of the kind described, a plurality of substantially flat plates, flanges struck up from said plates to form apertures 15 therein, tubes provided with substantially flat sides and arranged in said apertures, said apertures being larger than said tubes and said flanges being arranged to engage said tubes, the flanges being of such size and shape 20 that air may pass freely between any one of said tubes and the flanges engaging it, the flanges being perforated to permit passage of air therethrough.

4. In a device of the kind described, a plurality of substantially flat plates, flanges struck up from said plates to form apertures therein, tubes provided with substantially flat sides and arranged in said apertures, said apertures being larger than said tubes and 25 said flanges being arranged to engage said tubes, the flanges being of such size and shape that air may pass freely between any one of said tubes and the flanges engaging it, and smaller flanges struck up out of said plate, 30 said smaller flanges of all the plates being arranged at regular intervals and on the same side of said larger flanges.

In testimony whereof, I have hereunto signed my name.

ARTHUR B. MODINE.
